UNITED STATES PATENT OFFICE

109,063

DESIGN FOR AN AUTOMOBILE RADIO ANTENNA

Edgar J. Kern, Shreveport, La.

Application September 3, 1937, Serial No. 71,440

Term of patent 7 years

To all whom it may concern:

Be it known that I, Edgar J. Kern, a citizen of the United States, residing at Shreveport, in the parish of Caddo and State of Louisiana, have invented a new, original, and ornamental Design for an Automobile Radio Antenna, of which the following is a specification, reference being had to the accompanying drawing, forming part thereof.

Figure 1 is a side elevational view of an automobile radio antenna showing my new design.

Figure 2 is a cross-sectional view on line 2-2

of Figure 1 showing the body and fin portion of the antenna.

Figure 3 is a cross-sectional view of the body portion of the antenna taken on line 3-3 of Figure 1.

The body portion of the antenna is circular in cross section throughout its length.

I claim:

The ornamental design for an automobile radio antenna, as shown and described.

EDGAR J. KERN.
